UNITED STATES PATENT OFFICE

2,357,706

HEATING AND COOLING SYSTEM

Gustav A. Toepperwein, Los Angeles, Calif., assignor to Radio Corporation of America, a corporation of Delaware

Application June 29, 1942, Serial No. 449,029

5 Claims. (Cl. 18—5.3)

This invention relates to heat control systems and particularly to a method of and means for increasing the efficiency of systems wherein certain units are alternately heated with high temperature fluids and cooled with relatively low temperature fluids.

In the manufacture of many articles such as disc type phonograph records, the record molds are cooled during the molding operation and heated during the remaining portion of the pressing cycle. In this manner the shellac compound or other record material flows evenly between the matrices without excessive pressure at any point during the heating portion of the cycle. The record molds are generally heated by steam and cooled by cold water alternately passed through the interior of the molds. In the past the procedure has been to pass the emergent steam and cold water into a common outlet pipe where it was fed to a cooling tower and used over again as the cold water supply with a certain amount being by-passed for boiler feed water. This arrangement of course, required a certain boiler capacity to maintain an adequate supply of steam at the desired temperature.

The present invention is directed to a diversion valve system whereby the steam and cold water are separated after passing through the molds, the steam condensate being returned to the boiler feedwater tank and the cooling water passing on to the cooling tower. By this arrangement the boiler capacity required for a given number of presses has been considerably reduced, while better and more efficient heating of the record molds has been obtained, as will be explained hereinafter. Better heating of the molds has resulted in longer life of the molds and the production of a higher percentage of salable records.

The principal object of the invention, therefore, is to provide improved means for facilitating the manufacture of phonograph records.

Another object of the invention is to provide means for reducing the boiler capacity of a heating system for record presses.

A further object of the invention is to provide improved means for heating record molds and for conserving heat energy of the heating system.

A further object of the invention is to provide an improved phonograph record-pressing system having a minimum heat source capacity for a given number of presses operating in alternate short time cycles of heating and cooling.

Although the novel features which are believed to be characteristic of this invention are pointed

out with particularity in the claims appended hereto, the manner of its organization and the mode of its operation will be better understood by referring to the following description, read in conjunction with the accompanying drawing, in which:

Fig. 1 is a diagrammatic arrangement of a phonograph record press heating and cooling system embodying the invention.

Fig. 2 is a cross-sectional view of a thermostatic valve unit used in the system of Fig. 1; and,

Fig. 3 is a detail view taken along the line 3—3 of Fig. 2.

Referring now to Fig. 1, a plurality of phonograph record presses are shown diagrammatically as having lower fixed molds, 5, 6, 7 and 8 and respective movable molds 10, 11, 12 and 13. Each mold has an individual valve such as shown at 15 to 22, inclusive, each valve being adjusted individually to vary the steam and cold water to its respective mold in accordance with the position and size of each mold. After these valves are once adjusted they remain fixed. Steam is supplied to the molds from a steam generator or boiler 25 over a pipe 26, the steam being fed to valves 28, 29, 30 and 31. Cold water from a supply tank 33 is fed over a pipe 34 shown in dotted lines to valves 28, 29, 30 and 31, these valves being either manually or automatically operated so that either steam or cold water is fed to the respective molds 5 to 8 and 10 to 13.

Emergent steam and water from the molds 5 and 10 pass through a common pipe 36 to a thermostatic valve unit 37; the steam and water from molds 6 and 11 pass through a common pipe 38 to thermostatic valve unit 39; the steam and water from molds 7 and 12 pass through common pipe 40 to thermostatic valve unit 41; and the steam and water from molds 8 and 13 pass through pipe 42 to thermostatic valve unit 43. The thermostatic valve units 37, 39, 41 and 43 have two outlets, one shown by the solid line 45 which is a pipe leading to a feed-water tank 46, while the other outlet is shown by the dotted lines 48 which is a pipe leading to a cooling tower 49. In the above description and drawing, auxiliaries such as pumps and main valves have not been shown. It is also to be understood that many more presses than the four illustrated may be connected to a single steam generator.

In the manufacture of shellac compound records with the above-described system, the shellac compound, after preheating, is placed on the lower fixed molds 5, 6, 7 and 8 and the upper molds 10, 11, 12 and 13 are moved in contact with

the compound and pressure applied. During the period that the molds are separated, steam is passed therethrough to heat the stamping matrices to a certain temperature. This is accomplished by adjusting valves 28, 29, 30 and 31 so as to connect pipe 26 to the molds, thus passing steam from boiler 25 to the molds, the upper and lower molds receiving a quantity of steam proportioned by the setting of valves 15 to 22. If all presses are operating, steam passes through common pipes 36, 38, 40 and 42 to the thermostatic valve units 37, 39, 41 and 43, these units operating to pass the steam and condensation through pipe 45 to the feed-water tank 46. During the next portion of the cycle of operation the valves 28, 29, 30 and 31 are adjusted to cut off the steam from pipe 26 and feed cold water to the molds from the supply 33 over pipe 34. When the cold water is passed to the thermostatic units 37, 39, 41 and 43, the units automatically adjust themselves to pass the cold water to pipe 48 and to the cooling tower 49. In actual operation each press may be operated at different times, but in each case the respective thermostatic unit will divert the steam to the feed-water tank and the cold water to the cooling tower.

To illustrate the automatic operation of the diversion valve unit, reference is made to Fig. 2, wherein is shown any one of units 37, 39, 41 and 43 such as unit 37, having the common inlet pipe 36, a steam and condensation outlet pipe 45 and the cold water outlet pipe 48. The valve assembly comprises a casing of two sections 50 and 51 bolted together by bolts such as shown at 53. Longitudinally positioned within the casing is a thermostatic element 55 of the bellows type, one end of which is connected to an actuating rod 56 on which is mounted a valve 57 adjacent the other end of rod 56. The valve 57, upon expansion of the element 55, will seat itself against valve seat 59 and upon contraction of the thermostatic element 55 will seat itself against valve seat 60. The thermostatic element 55 is in a chamber 62, the chamber 62 being connected through a passage 63 with valve chamber 58. A passage 61 connects chamber 58 with outlet pipe 45 while a passage 68 connects chamber 58 with outlet pipe 48. A positioning and adjusting plate 64 is provided at the end of the casing 50. Plugs 65 and 66 are provided for cleaning the passage 63 when necessary. The end of the actuating rod 56 for the valve 57 is supported in a spider 67, as shown in Fig. 3. Although the valve unit is shown in a horizontal position, it is to be understood that the valve will function in a vertical or any other position and that the exact form may not be as illustrated.

When steam passes to the thermostatic element 55 through the pipe 36, the valve expands, moving the rod 56 and the valve 57 to the right. This movement of the valve 57 closes the outlet from chamber 58 to passage 68 and to the pipe 48 and permits the steam to pass from the chamber 58 to passage 61 and to the pipe 45 and back to the feed-water tank 46. When the cold water enters the chamber 62, it contracts the thermostatic element 55, moving the rod 56 to the left to close the steam outlet 57-60. This movement opens the cold water outlet 57-59 to pipe 48, and the cold water is permitted to flow to the pipe 48 and to the cooling tower 49.

From the above it is readily realized that the present invention prevents the mixing of the high and low temperature fluids by diverting or separating the steam and condensate from the

cold water immediately after each has served its purpose. By returning the steam and condensate back to the feed water for the boilers, it increases the temperature of the feed water above what it would be if the mixture were returned, thus requiring less fuel or boiler capacity to supply a given number of operating presses. The cooling water is also not heated by the steam and less cooling tower capacity is required.

As mentioned above, it has also been found that the invention provides better heating of the record molds, resulting in a longer life for the molds and the production of a higher percentage of salable phonograph records. This is accomplished by constructing the valve 57 and seat in the form of an orifice valve which holds the steam within the molds to approximately the condensation point. This result may also be accomplished by the use of a conventional steam trap in conjunction with the diversion valve, in which event the steam outlet 57-60 could be the same as water outlet 57-59. Without the diversion valve unit, a steam trap is not practical because of its inability to adequately handle the amount of cooling water necessary.

Thus, from the above, it will be noted that a more efficient transfer of the potential heat of the steam to the mold is obtained which, of itself, reduces the boiler capacity over that heretofore required. However, in addition a more uniform and rapid heating of the molds is obtained, which produces records in shorter time cycles. By the combination of the orifice steam valve or trap and the automatic diversion of the steam condensate and cooling water to their respective sources, more and a higher percentage of good records are obtainable.

I claim as my invention:

1. In a system for alternately heating and cooling an element with steam and water, respectively, including a common outlet valve mechanism for both said steam and water, said mechanism comprising a casing having an entrance opening for passing both said steam and water, an exit opening for said water only and an exit opening for steam condensate, a thermostat in said casing, and a valve head actuated by said thermostat for alternately opening and closing said exit openings, said exit openings for said condensate being proportioned to hold said steam within said element to substantially the condensation point thereof.

2. In a system for alternately heating and cooling a mold with steam and water, respectively, and for diverting said water to its source and steam condensate to its source, said system including a valve mechanism comprising a casing having an inlet opening for steam and water, an exit opening for said water, said exit opening being sufficiently large to accommodate the passage of said water, and an exit opening for steam condensate, said exit opening for said condensate being in the form of an orifice valve to hold the steam within said mold to approximately the condensation point thereof, a thermostat within said casing, and a valve head for alternately closing and opening said exit openings.

3. The method of cyclically heating and cooling an element by steam and water, respectively, and separating said water and steam and steam condensate which is formed, comprising passing said steam and water alternately through said element, passing said steam and condensate formed therefrom, and water from said element through a common passage with separate exits for said cooling water and combined steam and

steam condensate, releasing said water through said water exit at the rate of flow of said water through said element, releasing said combined steam and condensate at a rate to hold said steam within said element to approximately the condensation point thereof, and controlling the releasing of said water and said combined steam and condensate by the temperature of said combined condensate and steam, and said water, passing through said common passage.

4. The method of cyclically heating and cooling a mold by steam and water, respectively, and separating said water and steam condensate after passage through said mold, comprising passing said steam and water alternately into and out of said mold, diverting said water to its source after passage through said mold, diverting steam condensate to the source of said steam, the diverting of said steam condensate being accomplished at a rate to cause said steam to approximately 15 reach the condensation point within said mold, and controlling the diverting of said condensate

and said water by the temperature of said steam and said water.

5. A system for cyclically heating an element by steam and water, respectively, and diverting steam condensate and said water into separate channels including a valve mechanism comprising a casing, a thermostat within said casing, a pair of outlet ports in said casing, one for steam condensate and the other for said water, and a 10 valve head connected to said thermostat for closing said water outlet port and opening said condensate port when said thermostat is contacted by said steam and for closing said condensate outlet port and opening said water port when 15 said thermostat is contacted by said water, said water outlet port being sufficiently large to permit the ready flow of said water therethrough, and said condensate outlet port being in the form of an orifice valve to hold said steam within said 20 element to approximately the condensation point.
